UNITED STATES PATENT OFFICE

2,537,196

HUMIDOR TOBACCO POUCH

Alex Tanski, Brooklyn, N. Y.

Application August 21, 1946, Serial No. 691,966

3 Claims. (Cl. 312—31.2)

1
My invention relates to pocket pouches and refers particularly to pocket pouches adapted for use as humidor containers for tobacco, but their use is not confined to this particular purpose.

From among the many properties which must be possessed by pocket pouches for the protection of contained tobacco in a humidifying atmosphere, I mention the following. They must be made of pliable, folded material, the material must be non-porous to moisture, there must be separate pockets for the tobacco and the humidifying material, not capable of allowing the accidental mixture of the tobacco and the humidifying material, both pockets must be readily accessible for the introduction of the necessary tobacco and humidifying material, the tobacco pocket must be closely accessible for the removal to tobacco therefrom without interference with the humidifying pocket, they must be readily foldable into a minimum of space with complete prevention of seepage of tobacco and moisture therefrom, they must be easily manufactured and at low cost of production.

A consideration of my specification and its accompanying drawings shows that the devices of my invention possess all of the above, and other desirable properties.

My devices can be made of a single piece of proper material and its only step of procedure in its production is to make one slit in the material, form a small number of perforations therein and affix certain portions of the material together.

The completed pouch of my invention possesses a humidifying pocket, a tobacco containing pocket, perforations between the two pockets, and its form and construction are such that the tobacco is maintained from actual contact with the humidifying material.

While I have described its use as a humidifying tobacco pouch, my invention is not limited to pouches for this particular use, as it is evident that my devices are so constructed as to be suitable for containing any objects in which two separate pockets are desirable.

In the accompanying drawings illustrating one form of a device of my invention, similar parts are designated by similar numerals:

Figure 1 is a perspective view of one form of a device of my invention in partial folded position.

Figure 2 is a section through the line 2—2 of Figure 1.

Figure 3 is an end view of the device of Figure 1 in complete folded position.

2
Figure 4 is a section through the line 4—4 of Figure 1.

Figure 5 is a section through the line 5—5 of Figure 1.

Figure 6 is a front view of the device of Figure 1 showing the strip of material folded upon itself prior to the attachment together of the folded portions.

The device of my invention shown in the accompanying drawings comprises a single sheet of pliable material, preferably moisture-proof, doubled upon itself to form an elongated piece of the material having the back sheet 10 and the front sheet 11, their edge portions being attached to each other by any suitable means as at 12. The two sheets of the material thus abut upon each other throughout their entire side portions and top, and this double sheet of material is referred to herein as a pouch sheet. Various sections of this pouch sheet are referred to herein as A, B, C, D and E, and the imaginary limitations of these sections are designated by L—L, M—M, N—N and O—O, as shown particularly in Figure 6.

The end portion A of the pouch sheet has a slit 13 extending through the back sheet 10, but not through the front sheet 11, which slit 13 can be opened and closed if desired by the zipper 14 or by any other suitable means. The front sheet 11 of section B is perforated 15, 15 and the front sheet 11 of section C is perforated 16, 16 but not the back sheet 10.

The sections A and B are then folded along the line M—M and their edge portions attached to the edge portions of sections C and D as shown particularly in Figure 1.

The thus folded device has two pockets F and R, a front pocket F formed in section B by the slit 13 having a single sheet front wall and a single sheet back wall, the back wall having perforations therethrough, the second or rear pocket R is formed in sections A and B having a double sheet back wall, the inner sheet of this pocket having perforations therethrough, and the front wall of this pocket being double above the slit 13 and single below the slit 13.

The pouch when thus formed consists of a front pocket accessible through the slit 13 and having perforations opening into the rear pocket, and a rear pocket having perforations opening into the space between the back sheet 10 and the front sheet 11.

It is evident that instead of using a single sheet of material as particularly described and shown, 55 pouches of similar construction can be formed

by fixedly attaching two sheets of material along their four sides, such a device will not form the folded lower edge shown in the accompanying drawings, but if the two separate sheets are attached to each other the resulting pouch will be otherwise identical to that shown in the accompanying drawings.

When my device is used as a tobacco pouch, a moisture containing element, such as moistened absorbent paper, textiles or other adaptable material is placed in the front pocket and tobacco is placed in the rear pocket, and hence, while the tobacco is prevented from actual contact with the moisture containing material, the moisture may pass from the front pocket into the tobacco in the rear pockets through perforations 15, 15 and 16, 16.

When it is desired to close the pouch, sections A, D and E are folded forwardly along the line L, L, thus closing the moistening pocket, and section E is folded about the line O, O thus closing the tobacco pocket, and section E may be releasably attached to the outer face of section C by any convenient means.

It will thus be evident that my device is readily made from a single piece of material, that the tobacco contained therein may be moistened without possibility of mixture between the tobacco and the moistening material, and that it possesses all of the other valuable features set forth in my specification.

I do not limit myself to the specific size, shape, number, material or arrangement of parts as shown and described, as these may be varied without going beyond the field of my invention.

What I claim is:

1. A pouch comprising a double sheet of pliable, waterproof material, all edges of which are attached to each other, the lower portion of said double sheet being folded upon itself and the said edges thereof being attached to the edges of the unfolded portion of the sheet, thus forming a pocket for a substance to be maintained at a predetermined humidity, the inner sheet of the rear wall of said pocket having perforations therethrough and the outer sheet of the front wall having a transverse slit therethrough, thereby forming a single thickness walled pocket positioned forwardly to the first mentioned pocket for a moisture-containing element, and the rear wall of said forwardly positioned pocket having perforations therethrough, said perforations in both instances being adapted for transferring moisture from said element to the substance whereby the substance is substantially evenly humidified.

2. A pouch comprising a double sheet of pli-

able, waterproof material, all edges of which are attached to each other, the lower portion of said double sheet being folded upon itself and the said edges thereof being attached to the edges of the unfolded portion of the sheet, thus forming a pocket for a substance to be maintained at a predetermined humidity, the inner sheet of the rear wall of said pocket having perforations therethrough and the outer sheet of the front wall having a transverse slit therethrough, thereby forming a single thickness walled pocket positioned forwardly to the first-mentioned pocket for a moisture-containing element, the rear wall of said forwardly positioned pocket having perforations therethrough, said perforations in both instances being adapted for transferring moisture uniformly from said element to the substance, and means for opening and closing said slit.

3. A pouch comprising a double sheet of pliable, waterproof material, all edges of which are attached to each other, the lower portion of said double sheet being folded upon itself and the said edges thereof being attached to the edges of the unfolded portion of the sheet, thus forming a pocket for a substance to be maintained at a predetermined humidity, the inner sheet of the rear wall of said pocket having perforations therethrough and the outer sheet of the front wall having a transverse slit therethrough, thereby forming a single thickness walled pocket positioned forwardly to the first-mentioned pocket for a moisture-containing element, the rear wall of said forwardly positioned pocket having perforations therethrough, said perforations in both instances being adapted for transferring moisture uniformly from said element to the substance, and means for opening and closing said slit, the upper portion of said unfolded portion of said double sheet being adapted to fold over the pocket portion of said pouch.

ALEX TANSKI.
